TRAVERSE START CONTROL

Charles C. Walker Williams and Harold E. Balsiger,
Waynesboro, Pa., assignors to Landis Tool Company,
Waynesboro, Pa.

Application September 14, 1954, Serial No. 455,820

7 Claims. (Cl. 121—45)

This invention relates to hydraulic control mechanisms for machine tool carriages and the like.

One problem heretofore considered negligible has become important because of new procedures and more rigid requirements in grinding. This problem has to do with the starting characteristics of hydraulically driven members on machine tools such as work carriages in which the carriage is quite frequently inclined to start with a lurch rather than to accelerate smoothly to the required speed. This problem exists only after the carriage has been at rest for some time and not during reversal of the carriage once the carriage has been put in motion.

This invention proposes to solve the problem by providing substantially equal pressure on both sides of the hydraulic motor and then gradually reducing the pressure on one side to exhaust pressure.

It is an object of this invention to provide means for effecting a smooth start for a hydraulically actuated slide.

A further object is to provide means for resisting the movement of the carriage and thereafter gradually reducing the magnitude of resistance.

A further object is to provide a valve for blocking a discharge of exhaust fluid from a hydraulic motor and means for automatically shifting the valve to effect a gradual release of exhaust fluid.

Figure 1 shows a sectional diagram of a hydraulic control valve and a double piston motor such as used in some machine tool traverse mechanisms.

Figure 2 is similar to Figure 1 except that it shows the various valve members in operative position.

Numerical 10 indicates a valve body similar to that disclosed in Patent No. 2,249,343, granted July 15, 1941. It includes a start and stop valve 15 having ports 16 and 17 separated by a land 18. Fluid under pressure is supplied from a pump 34 through lines 20 and 21 to port 16. In the position of valve 15 as shown in Figure 1, ports 16 and 17 are cut off from one another. However, movement of said valve to the left will permit the flow of fluid under pressure from port 16 to port 17 and then through line 25, port 26 in the reversing valve and line 27 to the small end 28 of a valve 29. Fluid from port 26 also acts on the left end of by-pass valve 70. Fluid from line 20 also passes through line 35 having a restriction 36 therein to the right hand end of valve 29 for applying a reduced pressure on the left end of said valve. Between said restriction and said valve, a line 40 having a throttle valve 41 therein provides a restricted exhaust through which fluid is discharged from the right hand end of valve 29. Reversing valve 50 may be actuated to direct fluid under pressure from line 25 alternately through lines 30 and 31 to the head ends of cylinders 60 and 61. Exhaust fluid from said cylinders is directed by valve 50 to exhaust passage 65 which leads to port 66 in valve 29. Said valve in the position shown separates port 66 from port 67 which is connected to exhaust passage 68 leading to the reservoir.

The rod ends of said cylinders are connected by lines 75, 76, and throttle valve 77. Fluid from port 26 acts

2

on the left end of valve 70 to shift said valve to the right to stop the free passage of fluid between lines 75 and 76 and direct it through throttle valve 77. Lines 78 and 79 are air-bleeding lines.

5 Valve 29 is normally held in its left hand position by constant pressure from pump 34 acting through lines 20, 35 and restriction 36. The pressure holding valve 29 to the left is less than pump pressure because of the drop across restriction 36 and because of exhaust line 40. This pressure serves to reset valve 29 when start and stop valve 15 is shifted to the right, cutting off the pressure to the left end of valve 29.

When valve 15 is shifted to the left fluid under pressure in port 16 passes through port 17 and line 25 to reversing valve 50 which directs it through lines 30 or 31 to one or the other of cylinders 60 or 61. Exhaust fluid from said cylinders is directed by valve 50 to line 65 which is blocked by valve 29.

Fluid under pressure in line 25 also passes through line 27 to the left or small end 28 of valve 29 and shifts said valve to the right at a rate determined by the setting of throttle valve 41 in exhaust line 40. As valve 29 moves to the right it permits a gradually increasing flow of exhaust fluid from line 65 to pass through port 67 and line 68 to the reservoir. The gradual unblocking of exhaust line 65 permits the traverse motor to start smoothly.

We claim:

1. In a hydraulic system, a motor, a supply of fluid under pressure therefor, a reversing mechanism for directing fluid to drive said motor alternately in opposite directions, an exhaust passage connected to said reversing mechanism, a start and stop valve for controlling the supply of fluid to said reversing mechanism, a pressure operated valve normally blocking the exhaust passage from said reversing mechanism and means for shifting said valve to open said exhaust passage and means for controlling the rate of said shifting movement.

2. In a hydraulic system, a motor, a supply of fluid under pressure therefor, a reversing mechanism for directing fluid to drive said motor alternately in opposite directions, an exhaust passage connected to said reversing mechanism, a start and stop valve for controlling the supply of fluid to said reversing mechanism, a pressure operated valve normally blocking the exhaust passage from said reversing mechanism, connections between said start and stop valve and said exhaust blocking valve operable when said start and stop valve is moved to start position to direct fluid to shift said valve to open said exhaust passage and means for resetting said exhaust blocking valve when said start and stop valve is returned to stop position.

3. In a hydraulic system, a motor, a supply of fluid under pressure therefor, a reversing mechanism for directing fluid to drive said motor alternately in opposite directions, pressure and exhaust lines connected to said reversing mechanism, a start and stop valve for controlling the supply of fluid to said reversing mechanism, a valve in said exhaust line for blocking the exhaust passage from said reversing mechanism, said exhaust line valve having a large area end and a small area end and an intermediate portion, said start and stop valve being operable in the start position to direct fluid under pressure to said small area end, said large area end being under pressure at all times, the supply of fluid to said large area end being restricted so that the pressure on said large area end is less than the pressure on the small area end, an exhaust line connected to said large area end and having an adjustable restriction therein, whereby said exhaust valve may be moved by the pressure on the small area end at a rate determined by the restriction in the exhaust passage from the large area end, to gradually connect the

axially spaced ports to release said exhaust fluid from said reversing mechanism.

4. In a hydraulic system, a motor, a supply of fluid under pressure therefor, a reversing mechanism for directing fluid to drive said motor alternately in opposite directions, a start and stop valve for controlling the supply of fluid to said reversing mechanism, an exhaust passage connected to said reversing mechanism, an exhaust valve normally blocking the exhaust passage from said reversing mechanism, means for directing fluid under pressure to one end of said exhaust valve, an exhaust line from the other end of said exhaust valve, a restriction in said exhaust line to control the rate of movement of said valve when pressure is applied at the one end thereof, the means for directing fluid under pressure to one end of said exhaust valve including fluid connections between said start and stop valve and said exhaust valve for shifting said exhaust valve in a direction and at a rate for gradually opening said exhaust passage whereby to cushion the starting of said motor movement.

5. In a hydraulic system, a motor, a supply of fluid under pressure therefor, a reversing mechanism for directing fluid to drive said motor alternately in opposite directions, a start and stop valve for controlling the supply of fluid to said reversing mechanism, an exhaust conduit connected to said reversing mechanism, an exhaust valve normally blocking said exhaust conduit, means for directing fluid under pressure to one end of said exhaust valve, a constant supply of fluid under pressure to the other end of said valve including a restriction for reducing the pressure on said other end, an exhaust passage between said restriction and said exhaust valve and a throttle valve in said exhaust passage to control the rate of movement of said exhaust valve when pressure is applied at one end thereof, the means for directing fluid under pressure to one end of said exhaust valve including fluid connections between said start and stop valve and said exhaust valve for shifting said exhaust valve in a direction and at a rate for gradually opening said exhaust passage whereby to cushion the starting of said motor movement.

6. In a hydraulic system, a reciprocable motor, a supply of fluid under pressure for driving said motor, a reversing mechanism for directing fluid alternately to opposite sides of said hydraulic motor, pressure and exhaust connections to said reversing mechanism, means for blocking said exhaust connection and means for shifting said blocking means, and means to control the rate of shifting of said blocking means to release exhaust fluid at a controlled rate until the exhaust line is completely opened.

5 7. In a hydraulic system, a motor, a supply of fluid under pressure therefor, a reversing mechanism for directing fluid to drive said motor alternately in opposite directions, a start and stop valve for controlling the supply of fluid to said reversing mechanism, an exhaust conduit connected to said reversing mechanism, an exhaust valve normally blocking the said exhaust conduit, means for directing fluid under pressure to one end of said exhaust valve when said start and stop valve is in start position to open said exhaust valve and for connecting said end to exhaust when said start and stop valve is in stop position, a constant supply of fluid under pressure to the other end of said exhaust valve for resisting the opening thereof, an exhaust line connected to the same end of said exhaust valve as said constant supply and having an adjustable restriction therein to control the rate of opening said exhaust valve, said constant supply of fluid under pressure serving to reset said exhaust valve when said start and stop valve is in stop position.
